UNITED STATES PATENT OFFICE.

WILLIAM L. DE HAVEN, OF WICHITA, KANSAS, ASSIGNOR OF ONE-EIGHTH TO CHESTER A. LATHAM, OF WICHITA, KANSAS.

BALL-THROWING TOY.

1,309,614.

Specification of Letters Patent. Patented July 15, 1919.

Application filed March 13, 1917. Serial No. 154,480.

To all whom it may concern:

Be it known that I, WILLIAM L. DE HAVEN, a citizen of the United States, residing at Wichita, in the county of Sedgwick 5 and State of Kansas, have invented a new and useful Ball-Throwing Toy, of which the following is a specification.

This invention relates to improvements in toys and more particularly to ball-throwing 10 toys, the object of which is to provide an arrangement that will pocket the ball every time after the ball has been tossed.

A further object of this invention is to provide a toy that will toss the ball through 15 a horizontal ring into a basket or pocket formed with an opening in the bottom and return the ball to the projector.

With these and other objects in view my invention consists in the construction, combination, and arrangement of parts disclosed in the drawings and specification, and then more particularly pointed out in the appended claims.

In the drawings, wherein similar reference characters designate similar parts, in 25 the respective views,

Figure 1 is a longitudinal view partly in section,

Fig. 2 is a cross-sectional elevation taken 30 on line A—A of Fig. 3,

Fig. 3 is a bottom plan view of the invention,

Fig. 4 is a longitudinal elevation thereof,

Fig. 5 is an end elevation of the invention, 35 and

Fig. 6 is a perspective view of the projector to be described.

Referring to the drawings which are merely illustrative of my invention, the details of construction thereof are disclosed. 40 The bottom or base portion C of the device is of peculiar construction in that it is formed with a diamond-shaped recess H extending from one end of the device to the other and this recess sets apart between its inclined edges or sides and the adjacent walls of the rectangular inclosure D four guide walls C''' which converge toward the longitudinal center of the device to 45 form a floor, which also inclines from high at its central portion to low toward its opposite ends as at c, c''. It will be seen that the floor as well as the guide walls slant so as to form in effect a track so that a ball 50 falling upon the guide walls is directed

upon the floor and the latter will direct the ball downwardly toward the ends of the inclosure. The inclination of the diamond-shaped contour of the floor causes it to provide oppositely-extending downwardly-inclined portions which converge up to a point where they are wide enough to provide circular depressions on pockets c' and c'' sunk below the level of the floor.

A pair of arms e and e' extend vertically 60 from the summit of the floor and serve to suitably support a ring E large enough to allow a ball to drop therein and projecting partially over one and partially over the other inclined side portion of this floor. The 65 sides of the inclosure D will preferably be made of wicker-work or basket material as illustrated at D'. In order to provide propulsion mechanism for a ball the projectors I illustrated in Fig. 6 are used made pref- 70 erably from a length of wire bent at a right angle as at J and having an integral terminal crank f' formed thereupon, while at the opposite end of this projector arm I is formed an integral ball-seating ring F. 75 Two of these projectors are employed and the bent portions J of these projectors are suitably trunnioned within staples h h' and h'' h''' respectively secured upon the sum- 80 mit of the floor H, in such a manner that 85 the cranks thereof project laterally of the sides of the inclosure D and so that the arms I thereof will normally incline downwardly upon the inclined portions of the floor as shown in Fig. 1; the rings F thereof being 90 slightly offset so as to project into the de- 95 pressions or pockets c', c''. It is understood that a ball G will be placed upon the ring F of the arm I of either projector. It will now be seen that by taking hold of the 100 crank f' of either projector and turning the same around the arm I will be actuated so as to lift the ball G or G''' along with the same and toss it as indicated by the dotted line G'' upwardly and forwardly in the di- 105 rection of the stationary ring E. By im- parting to the projector the proper amount of force the ball seated upon the ring F thereof will be tossed and swung in the air far enough to drop into the ring E, and 110 thence upon the track formed conjointly by the floor and guide walls of the inclosure and will thence be suitably guided into either of the depressions c', c'', being thus pocketed, and if the ring F of a projector 110

happens to be seated in this pocket, or depression it will be seen that the ball will be suitably lodged upon the ring of this particular projector ready to be tossed over again in the manner disclosed.

5 In this way it will be seen that a novel and entertaining toy is provided which will be a delight to children. Numerous modifications may be made in practice without departing in principle from the details herein disclosed.

10 In this application I desire to claim:—

15 1. In a device as described, in combination, a base-board, having oppositely-inclined sides, four walls forming an inclosure thereabout, a pair of vertical arms extending from the center of said base-board, a ring held upon said arms projecting over said each inclined side of said base-board, 20 said base-board being formed with a depression at its opposite ends, ball-throwers carried by said base-board and having rings seatable in said depressions.

25 2. In a device as described, in combination, an inclosure, composed of side walls,

and a base-board, said baseboard being formed with oppositely-inclined and converging tracks, the side walls of which flare toward the walls of said inclosure, depressions formed in said base-board at the outer 30 ends of said tracks, a ring supported above the center of said baseboard between said track adapted to allow passage of a ball therethrough and means for tossing a ball into said ring.

3. In a device as described, in combination, an inclosure, a base-board therein having outwardly flaring and converging side walls, and outwardly converging oppositely-inclined longitudinal portions formed terminally with depressions, and a pair of projections made of wire and each having an arm overlying one of said inclined portions, an integral rightangular portion trunnioned on said base-board having cranks outside 45 the inclosure, said arms having rings at their outer ends adapted to seat in said depressions, and receive and hold balls.

35 WILLIAM L. DE HAVEN.
